UNITED STATES PATENT OFFICE.

JAMES H. MOYER, OF COLUMBUS, OHIO, ASSIGNOR TO THE COLUMBUS DENTAL MANUFACTURING COMPANY, OF COLUMBUS, OHIO, A CORPORATION OF OHIO.

CARDING DEVICE FOR ARTIFICIAL TEETH.

Application filed March 24, 1926. Serial No. 96,957.

This invention relates to an improved carding device for effecting the mounting and display of artificial teeth, and the primary object of the invention resides in the provisions of a carding device of this character wherein provision is made for the display of symbols or other identifying indicia for use in connection with the device but wherein changes may be made from time to time in the symbols or other indicia without effecting the carding device itself.

It has been the practice heretofore to produce a carding device wherein the metal or other material constituting the base of the device has been stamped or otherwise marked with the symbols or indicia employed to identify the particular artificial teeth mounted thereon. This has resulted in providing a permanent application of the symbols to the carding device, thereby limiting the device to the particular grade of teeth initially arrayed thereon. In accordance with the present invention this limitation is overcome by providing the carding device with an interchangeable means by which symbols and identifying indicia of various kinds may be applied to or removed from the carding device at will, so that the field of usefulness of said device is greatly enlarged.

It is another object of the invention to provide a carding device wherein the same is provided with an opening arranged in registration with a removable indicia bearing member interchangeably mounted upon the rear face of the device whereby the indicia will be viewable through said opening, but wherein substitutions may be quickly and easily effected so as to enable varying symbols to be employed in connection with any one of the carding devices formed in accordance with the features herein.

For a further understanding of the invention reference is to be had to the following description and the accompanying drawing, wherein;

Figure 1 is a front elevation of a carding device for effecting the display of artificial teeth, and wherein said device is shown as formed in accordance with the present invention,

Figure 2 is a rear elevation thereof,

Figure 3 is a vertical sectional view on the line 3—3 of Figure 1, on a slightly larger scale,

Figure 4 is a rear elevation of a slightly modified form of the invention,

Figure 5 is an edge view thereof,

Figure 6 is a front elevation disclosing a further modified form of the invention,

Figure 7 is a horizontal sectional view taken on the line 7—7 of Figure 6, and

Figure 8 is a further modified form of the invention.

Referring more particularly to the drawing the numeral 1 designates in its entirety the improved carding device comprising the present invention. In its present method of construction the device is formed to comprise a sheet metal base 2 upon the front of which is mounted a metallic retaining strip 3, which carries a plurality of lugs 4 that are capable of being received within slots 5 provided in the lingual faces 6 of the artificial teeth 7 formed in connection with the base. The specific means for detachably connecting the teeth 7 with the base 2 do not enter directly into the present invention, as it is in the scope of the latter to employ any suitable means for detachably connecting the teeth of the carding device depending upon the structural peculiarities of the teeth to be so supported. For example, certain artificial teeth are formed with laterally projecting pins and, as shown in Figure 6, a base 18 is provided by which teeth of this construction are detachably connected therewith. It is obvious, therefore, that many different types of securing devices and means may be employed for separably uniting the artificial teeth with the front surface of the carding device and it is considered within the scope of this invention to use such means in this respect as may be deemed advisable or necessary. The specific means disclosed in Figures 1 and 3 forms the subject matter of the United States patent issued to Pickering No. 1,496,168 dated June 3, 1924.

In accordance with the present invention the base 2 is provided with one or more openings 9 which are arranged adjacent to instructive indicia 10 suitably provided on the outer surface of the base. Arranged to register with one or more of these openings is a plate 11 which in this instance is slidably received between the down-turned flange 12 provided upon the upper longitudinal edge of the base and a pair of laterally extending lugs 13 projecting outwardly from the rear face of said base, the plate being also en-

gaged by a resilient tongue 14 carried by the rear surface of the base, and which exercises a frictional pressure on the plate to retain the latter and its symbols, indicated at 15, in registration with the sight openings 9.

From this construction it will be observed that in lieu of permanently marking the carding device, the present invention provides for an interchangeable marking thereof. For example, artificial teeth are usually identified by their form and color, each form bearing a certain identifying symbol and likewise the color. By the present invention the mere insertion of the plate 11, which may be in the nature of a card-board strip, into operative relation with the carding device, I am enabled to identify any particular grouping of teeth which may be placed on the device. If later on a different grouping of teeth is provided having other physical characteristics, I remove the first card and substitute a second card which corresponds to the latter applied teeth. This construction, therefore does away with the necessity of marking the carding device for each group in a permanently impressed form and substitutes a much more flexible and readily controlled system of identification. In the case of the invention disclosed in Figures 4 and 5 the longitudinally extending stiffening flanges 16 provided upon the edges of the device are notched so as to provide inwardly bent lugs

17 which serve to resiliently retain the plate 35 or card 11 in registration with the sight opening as previously explained.

In the form of the invention disclosed in Figures 6 and 7 the base 18 of the carding device has its forward face provided with a plurality of integral outwardly struck tongues 19, which constitute a holder in which a replaceable symbol bearing card 20 is adapted to be mounted. In Figure 8 the base 21 of the carding device is formed from celluloid or some other transparent or semi-transparent material, and in this case the symbol bearing strip is mounted on the back side of the base and is viewable because of the transparent properties of the 50 material constituting the base.

What is claimed is:

A carding device of the character described comprising a display plate having openings therethrough near the upper edge 55 thereof and occupying a comparatively small area of the plate, holding means on the rear of and at the top and bottom edges of the plate, and an indicia card substantially coextensive with said plate and detachably held thereto by said holding means and bearing indicia for display through said openings, the lower part of the plate having a display of goods on its face.

In testimony whereof I affix my signature.

JAMES H. MOYER.
